UNITED STATES PATENT OFFICE

WILLIAM F. DETWILER, OF TARENTUM, PENNSYLVANIA, ASSIGNOR TO ALLEGHENY STEEL COMPANY, A CORPORATION OF PENNSYLVANIA

FURNACE CONSTRUCTION

Application filed April 27, 1928. Serial No. 273,256.

This invention relates to furnaces and more particularly to an improvement in the construction of furnaces for heat treating sheet metal and the like.

5 Heating furnaces in general have heretofore been constructed of fire brick or blocks of like refractory material, or they have been provided with a lining of fire brick or like refractory material. Such materials, when subjected to great heat, expand and contract and cause cracks allowing heat to escape from the furnace. Such material as fire brick and the like does not only crack under the condition of expansion and contraction, but spalls 10 and falls in contact with the material being treated, resulting in undesirable marking of such material. All of the furnaces known to me that are constructed from fire brick or have a lining of fire brick or like refractory material frequently fuse and burn out and of course it is necessary to be continually repairing such furnaces. This is not only expensive, but renders the furnace inoperative during such frequent repairs. Also in furnaces 15 designed for heat treating sheet metals, it is necessary for such metals to come in contact with the inner side walls of the furnace and such contact is very detrimental to the refractory walls and it is one object of this invention to provide a furnace, wherein the inner side walls are constructed of metal having sufficient refractory characteristics to withstand the heat of the furnace, retain the static pressure therein, eliminate cracks in the 20 furnace walls, eliminate the hazard of foreign material coming in contact with the sheets of metal being treated and eliminate the need of frequent repairs.

I have found through experience that sheets 25 of ferrous alloys containing 8% of chromium or above possess the required refractory characteristics for use as lining in heating furnaces and that such sheets will not crack under the conditions of expansion and contraction, nor do such sheets spall or fall in contact with the material being treated, also such refractory sheet metal, when employed as a lining for heating furnaces, will last indefinitely and thereby eliminate the expense 30 of frequently repairing such furnaces as is the

case when fire brick or like refractory materials are employed.

Another object of this invention is to provide a heating furnace that shall be simple and rugged in structure, inexpensive to manufacture and more efficient in operation than any furnace heretofore known to me. 55

These and other objects that may be made apparent throughout the further description of the invention are attained by means of the furnace illustrated in the accompanying drawings, wherein,

Fig. 1 is a longitudinal sectional view more or less diagrammatic of a furnace embodying the invention, and

Fig. 2 is a sectional view taken along the line II—II of Figure 1.

The present invention may be employed in the construction of furnaces of any desired shape or form and for the purpose of illustration, I have shown a furnace constructed for heating sheet metal. The furnace comprises a fire compartment 11 and a heating compartment 12. The conventional bridge wall 13 is provided between the compartments 11 and 12 and have associated therewith ash baffles 14 and 15. 70

The side walls and the top of the furance comprise a double metal wall 16 and 17 spaced apart having any suitable insulating material 18 disposed therebetween. The inner wall 16 is formed from sheets made from a ferrous alloy containing a high per cent of chromium and possessing the desired refractory characteristics for withstanding great heat. The outer wall 18 may be of any suitable metal, such as steel and the insulation 18 may be either silica sand or fire brick 19, as shown 75 within the bridge wall 13. 80

The furnace is preferably disposed on a cement foundation, as shown at 21. The heating compartment 12 is provided with a floor of refractory sheet metal 16 supported by metal supports 22 which are in turn supported by a steel plate 23. Between the steel plate 23 and the concrete foundation 21 is disposed any suitable insulating material as 18. 85

The fire compartment 11 is provided with a stoker 24 and grate 25 which is adapted to operate in the convenient manner. The en- 90 95 100

tire inner walls of both the fire compartment 11 and the heating compartment 12, as well as the baffles 14 and 15, are constructed of the refractory sheet metal 16.

5 An opening 26 is provided in front of the compartment 12 for inserting and withdrawing sheet metal to and from the furnace. The opening 26 is provided with a suitable door 27 constructed of the same material as the side walls and provided with any suitable means, such as shown at 28 for raising and lowering it.

The arrows 30 indicate the direction of movement of the gases through the furnace.

15 The gases in their passage from the fire compartment 11 to the heating compartment 12 pass around through the passages 31 and 32 formed by the bridge wall 13 and baffles 14 and 15 and during such passage are freed from foreign substances such as ashes, which are retained at the bottom of the compartment 33 formed by the bridge wall 13 and baffle 15, the compartment 33 is provided with a door 34 for removing such ashes therefrom. The gases circulate within the compartment 12 and pass out through openings 35 provided in the floor of the compartment 12 through the ducts 26 beneath the floor and out the stack 37.

30 I have found through experience that a heating furnace constructed in accordance with the above will last indefinitely and provide advantages lacking in any other furnace construction known to me. The inner walls or lining of the entire furnace, which is constructed from sheets of ferrous alloys containing a high per cent of chromium will positively withstand the heat required of such furnaces and will not crack, as do refractory materials, such as fire brick, that have heretofore been employed for this purpose.

Another important advantage of the present construction is that the static pressure is positively retained within the furnace and thereby renders the heating of metals in such furnace more uniform, efficient and less expensive.

Other advantages will be apparent to those skilled in the art, such as the elimination of the undesirable marking of the metals being treated by the dropping out of particles of the inner walls as is the case when fire brick or other like refractory materials are employed.

55 While I have illustrated and described, but one embodiment of this invention, it will be apparent to those skilled in the art that certain changes, modifications, substitutions, additions and omissions may be made in the invention without departing from the spirit and scope of the appended claims.

What I claim as new and desire to secure by Letters Patent is:

1. A heating furnace having in combination a combustion chamber, a heating cham-

ber, a bridge wall separating said chambers, an ash baffle spaced from said bridge wall extending from the bottom of said heating chamber to a point near the top thereof, a second ash baffle extending from the top of said heating chamber between said bridge wall and first mentioned ash baffle to a point near the bottom thereof, said ash baffles and bridge wall forming a passage for the products of combustion for delivering said gases to the top of said heating chamber and flues under said heating chamber for drawing the exhausted combustion gases from said heating chamber.

2. In a heating furnace having a combustion chamber, a heating chamber and a bridge wall, a lining for said chambers and a cover for said bridge wall formed from a sheet of ferrous alloy containing about 8% chromium and an ash baffle formed from a sheet of said alloy separating said combustion chamber from said heating chamber.

3. In a heating furnace having a combustion chamber, a heating chamber and a bridge wall, a sheet metal lining for the heating chamber and a cover for the bridge wall formed from a ferrous alloy containing at least 8% chromium, and an ash baffle separating the combustion chamber from the heating chamber and formed from sheet metal of the same alloy.

4. In a heating furnace having a combustion chamber, a heating chamber, a bridge wall and an ash baffle separating the combustion chamber from the heating chamber, a lining for the heating chamber and a cover for the bridge wall; said lining, cover and ash baffle being formed from ferrous alloy sheets containing at least 8% chromium.

5. In a heating furnace having a combustion chamber, a heating chamber and a bridge wall, a lining for said chambers and a cover for said bridge wall formed from sheet ferrous alloy containing at least 8% chromium.

In testimony whereof, I have hereunto subscribed my name this 24th day of April, 1928.

WILLIAM F. DETWILER.
